FLOOR-CONDITIONING ASSEMBLY FOR
FLOOR MAINTENANCE MACHINESRobert Fraser and Vernon Heath Tuson,
Beckenham, England

Application September 24, 1948, Serial No. 51,046

5 Claims. (Cl. 15—50)

1

This invention relates to floor conditioning assemblies for machines of the kind adapted for use in maintaining floors cleaned or polished.

An object of this invention is to ensure, in a machine adapted to be moved along a floor and having power-driven gyrating floor-conditioning units, that the said units are protected against the effect of their engaging a projection on the floor while in operation.

Further objects and advantages of the invention will be apparent from the following description of an embodiment thereof, as applied to a floor scrubber, which is given by way of example and with reference to the accompanying diagrammatic drawings, in which:

Fig. 1 is a side elevation of the complete scrubber part of one wall of a tank 95 for dirty cleansing solution being broken away to show its interior and one part (47) being broken away for better illustration,

Fig. 2 is a front elevation with a tank for soap solution and carrying handles omitted,

Fig. 3 is a section of a detail on the line 3—3 in Fig. 1,

Fig. 4 is a half plan view of the complete scrubber, an operator's handle being omitted,

Fig. 5 is a section of part of driving and control means for the brushes,

Fig. 6 is a section of a detail of these control means.

Fig. 7 is a section of an adjustable control valve for the cleansing solution.

Fig. 8 is a rear elevation of a fishtail nozzle, partly in section on the line 8—8 in Fig. 1, the rear end of the scrubber being removed to show details,

Fig. 9 is a section on the line 9—9 in Fig. 8,

Fig. 10 is a plan of part of the brush driving gear, sectioned on the line 10—10 in Fig. 5,

Fig. 11 is a side elevation of this gear, with only one of three brush-carriers in position.

A carriage, which is about 30 inches long, consists of a flat platform 20 roughly pear-shaped in plan, raised about 4½ inches above the ground and having a skirt-like flange 21 depending almost to ground level, the stem end of the pear shape being at the rear end of the carriage. The flange 21 follows a 180° circular arc at the front end of the platform and continues rearwards firstly as two parallel walls for a short distance and finally as two straight walls 21A converging towards the rear end of the carriage. The side portions of the flange 21 have rubber lips 22 extending down to floor level and serving as splash guards. The converging walls 21A are provided

2

with rubber lips which act on the floor as squeegees and each of which consists of two strips of rubber 23 and 24 (Fig. 3) held by screws 25 and a clamping strip 26 against the inner face of the wall 21A.

The carriage runs on two co-axial rubber-tired wheels 27 outside the flange 21 near the front end and two rubber-tired castors such as 28 between the walls 21A.

10 A sleeve-shaped housing 29 (Fig. 5) projects vertically through the platform 20 co-axially with the arcuate portion of the flange 21, and a hollow shaft 30 is slidable vertically and rotatable in a bushing 29' in the housing sleeve 29. The lower end of the shaft 30 projects below the platform 20 and is rigidly connected to a gear wheel 31. A lowering pin 32 passes co-axially through the hollow shaft 30 and is provided near its upper end with an annular abutment flange 33 co-operating with the upper end of the hollow shaft 30. A sun wheel 34, 6 inches in diameter and having a tire of friction material 35, is fast on the lower end of the pin 32. The hub of this wheel forms an annular abutment co-operating with the lower end of the hollow shaft 30. This shaft is therefore constrained to slide up and down with the pin 32 but can rotate around the pin. A helical spring 36 compressed between the upper end of the housing sleeve 29 and the flange 33 tends to keep the hollow shaft 30 and the pin in a raised position.

The gear wheel 31 has three spokes on each of which is mounted a lever 37 carrying a respective floor-conditioning unit and angularly movable about a vertical pin 38 fast in the spoke. Fixed to the free end of each lever 37 is a depending journal pin 39 carrying the floor-conditioning unit; in this embodiment the unit comprises a wheel-shaped brush backing member 40 which is 6 inches in diameter and the periphery of which is held in frictional engagement with the tire 35 of the wheel 34 fixed on the lower end of the lowering pin 32 so that the backing 40 acts as a planet pinion and the wheel 34 acts as a fixed reaction member. The brush backing has a central oil-less bushing 41 and is retained on the pin by a snap ring (not shown) engaged in a groove 42. The lower face of the backing 40 is provided with vertically depending bristles, only one tuft of which is shown at 43. The engagement of the rim of each backing 40 with the tire 35 is maintained by a tension spring 44 (Fig. 10) having one end anchored to a pin 45 on the gear wheel 31 and the other end acting on the lever 37; the torque imposed by the tension spring

44 on the lever 37 tends to rotate the latter on its bearing pin 38 in such a direction that the brush backing 40 is urged radially inwards into frictional engagement with the fixed tire 35.

An operator's handle 46 (Figs. 1 and 2) is forked at its lower end, the two prongs of the fork being pivotally mounted in bearing brackets 47, fixed on the platform 20, for rocking about a transverse axis. Tension springs 48 acting between the ends of the handle prongs and anchorages 49 on the brackets 47 bias the handle towards a vertical position.

Means are provided for preventing the lowering pin 32 from rotating and for causing it to be lowered under control of the operator to engage the brushes with the floor. These means include a bell-crank lever 50 (Fig. 5) capable of rocking in a transverse vertical plane about a pivot pin 51 carried by a dome 52 fixed by screws 53 to a flange 54 on the housing sleeve 29 and enclosing the upper part of the hollow shaft 30. The screws 53 pass through the platform 20, which is nipped between the dome 52 and the flange 54. One arm of the bell-crank lever 50 extends through diametrically opposed vertical guide slots 55 in the dome 52 and engages in a transverse slot 56 in the upper end portion of the lowering pin 32, whereby this pin is prevented from rotating. The other arm of the bell-crank lever terminates in an anchorage for a flexible cable 57 passing through a flexible casing 58 to a stirrup 59 (Figs. 1 and 2) pivoted to a hand lever 60 which is pivoted to a lug 61 on the handle 46. When the hand lever 60 is raised through 180° it draws the cable 57, and tension in the cable locks the lever in the raised position. The upper end of the casing 58 reacts against an abutment 62 fixed to the handle 46. The lower end of the casing 58 reacts against a plunger 63 slideable in a hollow adjusting screw 64 (Fig. 6) engaged in a tapped hole in one of the brackets 47. The plunger 63 is loaded by a compression spring 65 and thus forms a resilient abutment for the casing 58.

Movement of the flexible cable 57 to the left as seen in Fig. 5 causes downward movement of the arm of the bell-crank lever 50 engaging the lowering pin 32, so that the pin and the sun wheel 34 are moved downward against the action of the spring 36. Simultaneously, the gear wheel 31 is moved downward by the engagement of abutment flange 33 with the upper end of the hollow shaft 30, so that the three brush backing members 40 remain in engagement with the wheel 34. Thus, raising and lowering of the hand lever 60 causes downward and upward movement respectively of the brushes to engage them with and to disengage them from the floor, also respectively. The resilient abutment for the casing 58, provided by the plunger 63 and the spring 65, ensure that a sudden upward movement of the brushes, caused for example, by a projection on the floor, does not cause undue strain of the cable 57.

An electric motor 66 having a continuous rating of $\frac{1}{2}$ H. P. at 1400 R. P. M. is fixed to the platform 20. The motor spindle 67 (Fig. 11) projects below the platform and carries a pinion 68 engaging the gear wheel 31, the pinion being long enough to accommodate the rise and fall of the gear wheel. The reduction ratio is 98/11.

A tank 69 on the front of the platform carries cleansing solution. On the top of the tank is a filling funnel 70 adapted to receive a stream tipped from a bucket. The funnel is externally

of box-like form. A floor 71 slopes rearwards and downwards over the front half which is open, and a cover 72 encloses the rear half. Liquid passes from the funnel to the tank 69 through a transverse slot 73 at the rear of the base of the funnel. Two air vent pipes 74 open above the cover 72 and pass downwards into the tank in which they open horizontally.

A combined metering and stop valve 75 controls the flow of cleansing solution from the tank 69 to a pipe 76 which feeds the solution to a point in advance of the scrubbing circle. The valve 75 (Fig. 7) has a tubular body having at its inner end a screwed spigot 77 held in a hole in the tank 69 by a nut 78. An aperture 79 in a diaphragm wall is normally closed by a tapered needle 80 forming the tip of a plunger 81 slideable in a hollow adjusting screw 82 engaged in a screw-threaded part 83 of the valve body. A flange 84 on the plunger is a sliding fit in a cylindrical bore 85 in the body communicating with the delivery pipe 76. An enlarged portion 86 of the plunger is a sliding fit in a counter-bore formed in the inner end of the screw 82 and accommodating a helical compression spring 87 which biases the plunger towards the closed position. A resilient packing washer 88 is fitted between the flange 84 and the screw 82. The valve is opened by pulling the plunger 81 until it is arrested by the abutting of the flange 84 against the washer 88. This washer thereupon operates to prevent leakage of solution between the valve body and the adjusting screw and between this screw and the plunger. The position of the adjusting screw determines the degree of opening of the valve. A hand lever 89 (Fig. 2) on the handle 46 is pulled upwards by the operator's gripping the handle and pulls a flexible cable 90 led through a flexible casing 91 contained between an abutment 92 fixed to the handle 46 and an adjustable abutment 93 (Fig. 7) mounted on one of the brackets 47. The cable 90 is connected to the plunger by a close-coiled tension spring 94. When the hand lever 89 is operated, the initial movement of the cable 90 opens the valve 75 to the full extent permitted by the setting of the screw 82, the rest of the movement of the cable being accommodated by expansion of the spring 94.

On the rear part of the platform 20 is a closed tank 95 for dirty cleansing solution and surrounded by a single-stage centrifugal fan 96 directly driven by an electric motor 97 having a continuous rating of $\frac{3}{8}$ H. P. at 10,000 R. P. M. The fan inlet communicates with the tank 95 and the fan discharges to atmosphere. A sight glass 98 is marked to indicate the maximum working level of liquid in the tank 95, which is fitted with a drain valve 99.

A suction fishtail nozzle 100 (Figs. 1, 2, 4, 8 and 9) 21 inches wide is fitted transversely close behind the trailing ends of the squeegees 23, 24 and provided with a narrow slot-like mouth 101. Two rubber squeegee strips 102 and 103 are fixed to the back of the nozzle mouth by a clamping strip 104 and screws 105. The nozzle 100 is integral with a tubular stem 106 passing vertically upwards with a slight clearance through a standpipe 107 projecting upwards from the floor of the tank 95. The bore of the standpipe may taper slightly to a minimum at its top end. The upper end of the stem 106 projects above the top of the standpipe 107, the mouth of the latter being sealed by a rubber garter 108 stretched around the mouth of the standpipe and the part of the

stem projecting above this mouth. The stem consequently is free, within limits, to tilt laterally and to move longitudinally with respect to the standpipe. The nozzle is kept at right angles to the longitudinal axis of the machine by engagement of its end portions in guide slots 109 in the walls 21A. Two helical springs 110 compressed between the platform 20 and the nozzle 100 urge the latter towards the floor. The slight clearance of the stem 106 in the standpipe 107 allows the nozzle to assume a position slightly out of level if an uneven floor requires this. The stiffness of the rubber strips 102 and 103 in relation to the force exerted by the springs 110 is such that the rubber strips are bent as shown in Fig. 9 while the machine is operating and yet do not allow the lip of the nozzle to touch the floor. The rear strip 103 is slightly deeper than the front strip 102.

On the under side of the top of the tank 95 is an annularly dished deflector 111 (Fig. 1) aligned with the standpipe 107, and behind the deflector are two baffles 112 and 113 extending from side to side of the tank and from the top to a level below the mouth of the standpipe. A third baffle 114 extends from side to side of the tank and from its bottom nearly to its top between the baffles 112 and 113. The inlet to the fan 96 opens out of the tank behind the baffle 113.

Means for lifting the nozzle clear of the ground, in order to facilitate sluing of the machine or wheeling it idly, include a cam shaft 115 (Fig. 1) fitted with a hand lever 116 and journalled in the walls 21A. Two cams 117 fast on the shaft 115 co-operate with two levers 118 pivoted at one end to lugs 119 on the under side of the platform 20. The other ends of the levers 118 are engaged under pins 120 fixed in lugs on the nozzle 100. When the cams are in the position shown in Fig. 9, the nozzle is kept in its operative position by the springs 110. If the hand lever 116 is moved forwards the cams 117 raise the levers 118 and lock them in the raised position, so that the nozzle is held clear of the floor.

The machine is fitted with two lifting handles such as 121, which are omitted from Fig. 2.

In operation, the machine is manoeuvred, with the nozzle raised, to the point where it is required to start work, the lever 116 is operated to lower the nozzle, the motors 66 and 97 are switched on, and thereafter the hand lever 60 is raised to lower the brushes into contact with the floor and the hand-lever 89 is raised to start the delivery of cleansing solution through the pipe 76. The machine is now pulled or pushed slowly forward by means of the handle 46. The gear wheel 31 is rotated by the motor pinion 68 and the brushes are thereby rolled around the tire 35 which, being fixed to the shaft 32, is held stationary by means of the lever 50 so that the brushes perform a gyratory movement, imitating more or less the effect of hand scrubbing. It will be evident that the direction of rotation of the brushes relative to the gear wheel 31, is the same as the direction of rotation of this gear wheel relative to the floor. The brushes therefore tend to sweep the solution towards the axis of the gear wheel, and the solution is thus kept largely within the range of action of the brushes. The pressure with which the brushes bear on the floor is determined by the extent to which the spring 65 (Fig. 6) becomes compressed when the hand lever 60 is in its raised position, and the extent of compression of the spring 65 can be easily adjusted by varying the setting of the ad-

justing screw 64. The scrubbing pressure should be such that the tips of the bristles do the work, which is the correct action of a scrubbing brush and not such that the bristles tend to lie flat.

5 The minimum length of bristle depends on the irregularity of the floors to be worked on, the more irregular the floor level, the longer the bristle necessary. For general purposes a bristle projection of 1½ inches is satisfactory.

10 As the brushes scrub the floor, the forward motion of the machine causes dirty cleansing solution to be left behind the brushes, and this solution is wiped from the borders of the scrubbed part by the squeegee strips 23 and 24 and moved 15 towards the middle of the nozzle 100. The squeegee strips 102 and 103 on the nozzle prevent any substantial quantity of solution from being left on the floor behind the machine, the solution wiped up by these strips being carried up the stem 106 by the air current developed through the nozzle 100 by the fan 96. The deflector 111 directs the solution towards the bottom of the tank 95, and the air is substantially freed from traces of moisture by its sinuous passage around 20 the edges of the baffles 112, 114 and 113.

When the machine is required to be turned at the end of a straight run, the hand levers 60 and 89 are dropped to raise the brushes and interrupt the feed of cleansing solution, and the 30 hand lever 116 is moved forwards to raise the nozzle so that the machine can be easily turned or slued.

We claim:

1. A floor-conditioning assembly for a floor 35 maintenance machine, comprising a housing, a rotatable member, a bearing in said housing mounting said member for rotation about the axis of the bearing, a motor for rotating said rotatable member, a plurality of rotatable floor-conditioning units carried by said rotatable member and each including a planet pinion, a reaction member fixed relatively to the housing and engageable with the planet pinions, so that said units gyrate in response to rotation of the rotatable member, means mounting said units on the rotatable member and permitting translational movement of the units with respect to the rotatable member in a direction for disengaging the planet pinions from said fixed reaction member, and resilient members biasing said units for translational movement with respect to the rotatable member in the direction to engage the planet pinions with said fixed reaction member.

2. An assembly as claimed in claim 1, wherein 55 the said fixed reaction member comprises a stationary sun wheel and each planet pinion is frictionally engageable with said stationary sun wheel.

3. A floor-conditioning assembly for a floor-maintenance machine, comprising a housing, a rotatable wheel, a bearing in said housing mounting said wheel for rotation about the axis of the bearing, a motor for rotating the wheel, a plurality of arms pivoted to said wheel about 65 axes parallel to said bearing axis, a plurality of rotatable floor-conditioning units, each carried by the free end of one of said arms and each including a planet pinion, a reaction member fixed relatively to the housing and frictionally engageable with each planet pinion, so that the said units gyrate in response to rotation of said wheel, and springs biasing said arms for movement about their pivotal axes with respect to the rotatable wheel, so as frictionally to engage said 70 75 planet pinions with said fixed reaction member.

4. An assembly as claimed in claim 3, wherein said fixed reaction member comprises a stationary sun wheel and said planet wheels have their rims frictionally engageable with the rim of said stationary sun wheel.

5. An assembly as claimed in claim 3, wherein said floor-conditioning units include a plurality of backing members which are circular in plan forming the said planet pinions.
